WILHELM HENNING PETERSÉN, OF LUDVIKA, SWEDEN, ASSIGNOR TO ALLMANNA SVENSKA ELEKTRISKA AKTIEBOLAGET, OF VÄSTERÅS, SWEDEN, A CORPORATION OF SWEDEN.

INVERSE TIME-LIMIT RELAY.

Application filed May 26, 1921, Serial No. 472,848, and in Sweden October 7, 1926.

Relays of the inverse time limit type (that is relays where the time for releasing varies inversely as the operating current), as hitherto constructed, generally present certain disadvantages which prevent a satisfactory protecting action.

The most usual fault is probably the so-called "creeping" that is the timing mechanism of the relay beginning to move at a lower current value than that for which the relay is really intended to operate. If the current has, for a comparatively long time, been just a little below the operating value and then rises to or above this value, it may thus happen that the releasing is effected in much shorter time than is really intended.

Another fault, which is particularly frequent in solenoid relays, is that the return to the initial position, if the overload disappears before the releasing has occurred, is not effected until the current has dropped considerably below the value for which the relay started. Further the shape of the timing curve is often inappropriate, so that, for instance, the difference between the maximum releasing time—at the current value for which the relay is set—and the minimum time—at the highest possible current—is too large. If the relay is for instance set for 30 seconds releasing time at a certain overload current—the smallest value for which it releases—with many relays, at 4 to 5 times this current, the time drops to about two, or three, seconds and remains then constant at this value—the so-called short-circuit time—for any further increase in the current value until complete short circuiting of the line. Therefore if short-circuit occurs, there is nothing ensuring that differently timed relays perform their releasing action in the proper order.

The present invention relates to an inverse time limit relay of induction type which is free from the aforesaid disadvantages. The "creeping" is avoided by an arrangement such that the releasing mechanism is normally free from the operative device and is automatically connected thereto just when the latter, in moving, begins to develop its full torque (corresponding to the

releasing current value). By the same arrangement the return movement is also facilitated, because the coupling is released as soon as the torque drops below the aforesaid value. Since no constant torque counter-⁵⁵acting that of the current is needed for preventing the creeping, the speed of the driving device can be made any desired function of the operating current, whereby the shape of the time curve can be varied within wide ⁶⁰ limits. The ratio of normal releasing time to short-circuit time can therefore be varied at will down to 1:1.

The coupling of the driving device to the releasing mechanism can be effected, for instance, by means of a special magnet which is adjusted to act for a certain amount of current. The arrangement is, however, simplified, and the adjustment for different current values facilitated, if the torque acting upon the driving device be utilized for the coupling movement, the arrangement being such that the driving device is supported by a member capable of being swung into engagement position by a direct action of the ⁷⁵ said torque.

A construction, according to the invention, based upon the last-mentioned principle is shown in the accompanying drawing in side-elevation in Fig. 1 and in plan in ⁸⁰ Fig. 2.

The induction disc *a*, as usual, rotates between the poles of a driving electro-magnet *f* and between those of a braking magnet *g* with a speed proportional to the torque exerted by the first named magnet, which torque may, in its turn, be proportional to the exciting current. In hitherto known constructions of similar kind, the rotation of the induction disc has been counteracted by ⁸⁵ a weight, or a spring, or the like which has prevented said rotation until the torque has exceeded a certain value. According to the present invention, no such counteracting member is used, and the disc *a* can start ⁹⁰ rotating as soon as the induced torque exceeds the friction at rest—which can be reduced to a very low value by providing the disc with conical pivots. The releasing mechanism, on the contrary, is not normally

moved, since it is not coupled to the driving device. In the form shown, the transmission of the movement from the latter to the former is effected by a worm *h* engaging a toothed segment *i*. When the latter has been moved through a certain angle, it presses a movable contact piece *k* against a fixed contact piece *l*.

The engagement between the worm *h* and the segment *i* is, in the example illustrated, effected in the following manner. The shaft *p*, carrying the disc *a*, and the worm *h*, is journalled in a rocking frame *b*, fulcrumed on a shaft *c* parallel to the shaft *p*. The frame is balanced by a counterweight *n* which also by reason of its position between two stops *d* serves to limit the movements of the said frame. By means of an adjustable spring *e*, the frame *b* is normally held in such a position, that the worm *h* is not in engagement with the segment *i*. Assuming disc *a* to rotate in an anti-clockwise direction in Fig. 1, the magnetic forces acting upon it, which practically counterbalance each other with respect to the shaft *p*, exact a resultant torque in anti-clockwise direction about the shaft *c* which is situated at some distance from the shaft *p*. As soon as the current and, consequently, the torque have reached a certain value, the right hand end of the frame *b* is therefore raised so as to bring the worm *h* into engagement with the segment *i*. After a certain time, depending upon the current value, the segment forces the contact pieces *k* and *l* into contact with each other. Should the current, before that time, drop below the value for which the apparatus has been set, the engagement between the worm *h* and segment *i* is at once released whereupon the latter is returned to its initial position, which may be done, for instance, by means of a spring (not shown). For facilitating the releasing of the engagement between worm and segment, the motion of the former at releasing should be in a direction at an angle to the longitudinal direction of the teeth. The axis *c* should therefore have an eccentric position relatively to the centre plane of the segment.

The setting of the apparatus for different time limits is preferably effected by means of a screw *m* which defines the initial position of the segment. The setting for different current values may be effected in any known, or suitable, manner, for instance by connecting a greater or smaller portion of the coil *o* in the circuit, the said coil for this reason being shown with a plurality of taps. The critical current value for which the releasing mechanism begins to operate is in this manner automatically regulated, the engagement of the mechanism being dependent of the torque acting upon the operating device.

The feature of a permanently rotating op-

erating device—disc *a* and worm *h*—involves also an increased safety for the function of the relay in the event of an overload. When the engagement is effected, the segment *i* is immediately acted upon by a strong torque, especially on account of the kinetic energy stored in the disc *a*. Even if the segment should present a comparatively large initial friction, due to an extended period of inactivity, there is thus no danger that it will not be started at once.

Having now particularly described the nature of my said invention and the manner of its operation, I declare that what I claim is:

1. In inverse time limit relays, an electromagnet, an operating device kept in rotation around an axis under the influence of induction forces from said electromagnet and braking forces normally counterbalancing these, said operating device being capable of a swinging movement under a couple of forces formed by said induction and said braking forces.

2. In inverse time limit relays, an electromagnet, an operating device kept in rotation by induction from said electromagnet, a rocking frame supporting said operating device, and a releasing mechanism capable of being engaged by said operating device by rocking said frame.

3. In inverse time limit relays, an electromagnet, an operating device kept in rotation by induction from said electromagnet, a braking device for said operating device, a frame supporting said operating device and capable of rocking about an axis parallel to the axis of rotation of said operating device, and a releasing mechanism capable of being engaged by said operating device by rocking said frame.

4. In inverse time limit relays, an electromagnet, an induction disc capable of rotation under the influence of said electromagnet, a worm connected to said disc, a rocking frame supporting said disc and worm, a pair of contacts, and a toothed segment capable of being engaged by said worm by rocking said frame for actuating said contacts.

5. In inverse time limit relays, an electromagnet, an induction disc capable of rotation under the influence of said electromagnet, a worm connected to and rotating with said disc, a frame supporting said disc and worm and capable of rocking about an axis parallel to the axis of rotation of said disc and worm, a toothed segment capable of being engaged by said worm and having its center plane eccentric with respect to the rocking axis of said frame, and a pair of contacts capable of being actuated by said toothed segment.

6. In inverse time limit relays, an electromagnet, an induction disc capable of rotation under the influence of said electromagnet, a worm connected to said disc, a

toothed segment, a frame supporting said disc and worm and capable of being rocked so as to bring said worm into engagement with said segment, contacts actuated by said segment, and means for adjusting the initial position of said segment.

7. In induction relays, a rotatable induc-

tion member, electromagnetic means for rotating said member, and a counter-balanced rocking frame supporting said member. 10

In testimony whereof I have signed my name to this specification.

WILHELM HENNING PETERSÉN.
